UNITED STATES PATENT OFFICE.

IRWIN W. COX, OF DENVER, COLORADO.

DRY-STEAM SLEEVE-FINISHING BOARD.

Application filed November 26, 1926. Serial No. 150,846.

This invention relates to improvements in the construction of dry steam sleeve finishing boards of the type described and claimed in United States Letters Patent 1,592,655, granted on July 13, 1926.

It is the object of this invention to produce a sleeve finishing board of this type which shall be of simple, substantial construction, which shall be convenient and easy to operate and which shall be so made that the steam employed shall be as dry as practicable and in which the flow of steam can be made to cease almost instantly.

The above and other objects that will become apparent as the description proceeds are attained by means of a construction and arrangement of parts that I will now proceed to describe in detail, reference for this purpose being had to the accompanying drawing in which the preferred embodiment has been illustrated and in which:

Fig. 1 is a side elevation of my improved board, portions being shown broken away to better disclose the construction;

Fig. 2 is a detail looking in the direction of the arrows on line 2—2, Fig. 1;

Fig. 3 is a section taken on line 3—3, Fig. 1;

Fig. 4 is a section taken on line 4—4, Fig. 3;

Fig. 5 is a transverse section taken on line 5—5, Fig. 4;

Fig. 6 is a section taken on line 6—6, Fig. 4;

Fig. 7 is a section taken on line 7—7, Fig. 1;

Fig. 8 is a transverse section taken on line 8—8, Fig. 7;

Fig. 9 is a section similar to Fig. 6 and shows a modified form of construction; and

Fig. 10 shows a still further modification.

Numeral 1 indicates a base from the upper side of which the support 2 extends. Fas-
tened to the upper end of the standard 2 is a hollow casting 3 whose upper surface is flat and provided with a plurality of projec-
tions 4 which serve as supports for an iron,
a brush or a similar object. The sleeve arm
5 which has been indicated as a whole by num-
eral 5 is composed of an elongated U-
shaped pipe having two parallel arms 6 and
7 connected by the base portion 8. The
pipes 6 and 7 have been deformed so as to
have a flat surface 9. The other portions
of the surface are curved in the manner

shown in Figs. 5, 6 and 10 and are so as-
sembled that the flat surfaces will be up-
wardly and inwardly inclined. A plate 10
is welded to the upper surface of the pipes 60
and 7 and a similar plate 11 is welded to
the under surface so as to form with the
pipes a chamber 12. The pipes 6 and 7
pass through the interior of the chamber 3
and have ordinary reducers 13 threadedly 65
connected to their ends which are circular.
From Fig. 3 it will be apparent that the
shape of the cross section of pipes 6 and 7
changes as they extend through the casing
3. The sides of the pipes are secured to this 70
casing in such a manner that the joints will
be tight. The ends of plates 10 and 11 are
also welded to the casing so that chamber
12 will be in direct communication with the
interior thereof. As my device employs live 75
steam under considerable pressure, it is to
be understood that all joints must be steam
tight whether this is specifically mentioned
or not.

The plate 10 is provided with a plurality 80
of perforations 10^a (Fig. 4) and the entire
arm 5 is covered with padding 14 (Fig. 1).
From Fig. 4 it will be seen that the end of
the plate 10 which is nearest to the cas-
ing 3 is offset downwardly twice the thick-
ness of the material and that a plate 15 is
welded at its edges to the pipes 6 and 7 and
at its end 16 to the plate 10. A slide 17 is
located between plates 10 and 15 and has
a projection 18 which extends outwardly 85
through a slot in the plate 15 and by means
of which it can be moved. Plates 10 and
15 and the slide 17 are provided with a
plurality of holes 19 which register when
the slide is in one position but which are
out of register when the parts are in the
position shown in Fig. 4. The object of this
movable slide is to permit the operator to
cut off the flow of steam through this part
of the arm whenever he is operating on 90
sleeves that have fur cuffs or have cuffs of
any other material which might be damaged
by the steam. The reducer 13, which is con-
nected with the end of pipe 6, is connected
to a pipe 20 which extends to the boiler and
the reducer on pipe 7 is connected with the
pipe 21 which extends to and is connected
with T 22 (Fig. 1). A pipe 23 extends up-
wardly from T 22 and has its upper end
connected by means of the 180 degree con-
nector 24 with the downwardly extending
pipe 25, which connects with the quick act-

ing valve 26. A coupling 27 connects the lower opening of valve 26 with the T 28 from which a pipe 29 extends to the chamber 30 in the casing 3. A short coupling 31 connects the lower end of the T 28 with the quick acting valve 32 whose lower end is connected by means of a pipe 33 with the cross 34. An exhaust pipe 35 extends downwardly from cross 34 and communicates with some suitable drain. Valves 26 and 32 are identical and are operated in sequence by means of the following apparatus. A pedal 36 is pivoted at 37 and has a rod 38 connected to its free end; this rod extends through an eyelet 39 in the arm 40 of valve 32 and has its upper end connected with the lower end of the spring 41 whose upper end is connected with the free end of the lever 40 of valve 26. A stop 42 is secured to this upper end of the rod 38 a short distance above lever 40 of valve 32. The spring 41 is of such strength that it will open the valve 26 to full open position before the stop strikes the lever 39. If the pedal 36 is moved downwardly after the stop 42 reaches the lever 40 of valve 32, the latter will be opened. It is therefore evident that valve 26 will open before valve 32 can be opened and remain open until valve 32 has closed. When pressure is applied to the pedal 36, its first action will be to open valve 26 and let steam from pipe 21 flow through pipe 29 and into chamber 30, from which it may enter chamber 12 and pass outwardly through holes 10^a. In passing from pipe 29 to chamber 12 the steam must pass through the screen 43 (Fig. 4) which will catch any water particles and cause them to flow into the channel 44 from which the water will flow into pipe 45 and after passing through the seal 46 enter the exhaust pipe 35. A valve member 47 is secured to the end of the rod 48, which has a handle 49 by means of which it can be moved to the full line position (Fig. 4) in which position it prevents the steam from entering the chamber 12 and makes it flow upwardly through pipes 50 into the chamber 51 of the puffer 52 whose upper wall 53 is curved and provided with a plurality of openings 54. The bottom and sides of the chamber 51 are surrounded by another chamber 55 which is connected, by means of pipes 56 and 57, with the supply pipe 20 and the outflow pipe 21. When the valve 58 is open steam will circulate through the chamber 55 which serves as a heater and in this respect resembles pipes 6 and 7. When the plate 47 is in the position shown in Fig. 4 steam can be directed into chamber 51 from whence it will pass outwardly through openings 54. When the puffer is not in use valve 58 may be closed. The puffer 52 like the arm 5 is covered with a padding which 65 has been designated by numeral 59.

From the lower end of the T 22 a pipe 60 extends to the upper end of the filter seal 61 whose lower end is connected to the cross 34 by pipes 62. The function of the seal 61 is to permit the water of condensation from pipes 6 and 7 to escape slowly but continuously so as not to pass over the bend 70 75 80 85 90 95 100 105 110 115 120 125 130 From the lower end of the T 22 a pipe 60 extends to the upper end of the filter seal 61 whose lower end is connected to the cross 34 by pipes 62. The function of the seal 61 is to permit the water of condensation from pipes 6 and 7 to escape slowly but continuously so as not to pass over the bend 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790

trative of means broadly for this purpose. The slide 17 makes it easy to protect the fur or other material in the cuffs from the action of the steam while the valve 47 makes it possible to conveniently direct the steam to the puffer.

In the above description I have shown the pipe 23 as connected with the return pipe 21 which is also connected with the exhaust pipe 35. This arrangement gives a greater flow of steam through pipes 6 and 7 which will therefore be kept hotter. It is, of course, evident that I may connect pipe 23 with the intake pipe 20 and connect pipe 21 with the exhaust pipe 35 or with a return to the boiler, which latter has not been shown, with this arrangement less water of condensation is likely to enter chamber 30 than with the arrangement illustrated.

Referring to Fig. 4, it will be observed that between the openings to which pipes 29 and 45 are connected, there is a wall or partition member 144 which shields the channel from disturbance due to incoming steam and also serve to direct the steam against the screen 43.

Having thus described my invention what I claim as new is:

1. A steam sleeve finishing board comprising an arm consisting of an elongated member having three parallel chambers, one of which is located intermediate the other two, the two outside chambers being connected at one end, the top wall of the central chamber being perforated and connected to the walls of the outside chambers so as to form with the latter a convex surface and means for conducting steam to said chambers.

2. A steam sleeve finishing board having an arm consisting of an elongated tubular member having a continuous steam chamber having two parallel spaced portions, plates connecting the walls of said parallel portions so as to form a central chamber, one of the plates having a plurality of perforations, means for conducting steam to the central chamber and means comprising a slide for opening and closing said perforations.

3. A steam sleeve arm consisting of an elongated member having a steam conduit extending along both sides and across one end thereof, a central chamber having a foraminated wall, a foraminated plate slidably connected with the wall, means for conducting steam to the central chamber and means for moving said plate so as to bring the perforations thereof into or out of register with corresponding perforations in the wall.

4. A steam sleeve arm consisting of an elongated member having a steam conduit extending along both sides and across one end thereof, a central chamber having a foraminated wall, a portion of said wall

being formed from two thicknesses spaced apart, so as to form a space adapted to contain a slide, a plate slidable in said space, said plate and wall members having a plurality of openings that register when the slide is in one position, but which are out of register when the slide is in another position and means for conducting steam to the central chamber.

5. A steam sleeve arm consisting of an elongated member having a steam conduit extending along both sides and across one end thereof, a central chamber having a foraminated wall, a portion of said wall being formed from two thicknesses spaced apart, so as to form a space adapted to contain a slide, a plate slidable in said space, said plate and wall members having a plurality of openings that register when the slide is in one position, but which are out of register when the slide is in another position, a handle attached to the slide for moving the same and means for conducting steam to the central chamber.

6. A steam sleeve finishing board comprising, in combination, a support, an elongated arm secured to the support at one end and projecting outwardly therefrom, said arm having a steam conduit extending along both sides thereof, a steam chamber intermediate said conduit, said chamber having a foraminated wall, means for opening and closing some of said perforations, means for conducting steam to the chamber, means for conducting steam to one end of said conduit and a filter seal connected to the other end of said conduit.

7. A steam sleeve finishing board comprising, in combination, a support, an elongated arm secured to the support at one end and projecting outwardly therefrom, said arm having a steam conduit extending along both sides thereof, a steam chamber intermediate said conduit, said chamber having a foraminated wall, means for conducting steam to one end of said conduit, a filter seal connected to the other end of said conduit and a valved passage connecting the end of the conduit adjacent the filter seal to one end of said intermediate chamber.

8. A steam sleeve finishing board comprising, in combination, a support, an elongated arm secured to the support at one end and projecting outwardly therefrom, said arm having a steam conduit extending along both sides thereof, a steam chamber intermediate said conduit, said chamber having a foraminated wall, means for conducting steam to one end of said conduit, a filter seal connected to the other end of said conduit, a valved passage connecting the end of the conduit adjacent the filter seal to one end of said intermediate chamber, and a steam separator between said valved passage and the open end of the chamber for remov-

- ing the moisture from the steam before it enters the chamber.
9. A steam sleeve finishing board comprising, in combination, a support, an elongated arm secured to the support at one end projecting outwardly therefrom, said arm having a steam conduit extending along both sides thereof, a steam chamber intermediate said conduit, said chamber having a foraminated wall, means for conducting steam to one end of said conduit, a filter seal connected to the other end of said conduit, a valved passage connecting the end of the conduit adjacent the filter seal to one end of said intermediate chamber, a steam separator between said valved passage and the open end of the chamber for removing the moisture from the steam before it enters the chamber and a valve mechanism for closing the entrance to said chamber, a puffer having a steam chamber and means for connecting the interior of this chamber to the passageway between the valves.
10. A steam sleeve finishing board having a support, an elongated tubular perforated arm secured at one end to the support and extending outwardly therefrom and a conduit adapted to be connected to a source of steam, means for connecting the conduit and the interior of the arm comprising a T whose lateral opening is in communication with the interior of the arm, means for connecting one end of said T with the steam supply conduit, a quick acting valve between said T and the steam conduit, an exhaust pipe means comprising a quick acting valve for connecting the other end of the T with the exhaust pipe and means for opening and closing said valves.
11. A steam sleeve finishing board having a support, an elongated perforated tubular arm secured at one end to the support and extending outwardly therefrom and a conduit adapted to be connected to a source of steam, means for connecting the conduit and the interior of the arm comprising a T whose lateral opening is in communication with the interior of the arm, means for connecting one end of said T with the steam supply conduit, a quick acting valve between said T and the steam conduit, an exhaust pipe means comprising a quick acting valve for connecting the other end of the T with the exhaust pipe and means for opening and closing said valves, said means functioning to open the first mentioned valve before the second mentioned valve is opened and to hold the first mentioned valve open until the second mentioned valve is closed.
12. A combined steam sleeve finishing board and puffer, comprising an elongated tubular arm, a source of steam, a hollow puffing iron, a support having a chamber, means for connecting the interior of the

chamber with the source of steam, with the interior of the arm and with the interior of the puffing iron and a valve mechanism for closing the passageway from said chamber to the interior of the arm.

13. A combined steam sleeve finishing board and puffer, comprising an elongated tubular arm, a source of steam, a hollow puffing iron, a support having a chamber, means for connecting the interior of the chamber with the source of steam, with the interior of the arm and with the interior of the puffing iron, a valve mechanism for closing the passageway from said chamber to the interior of the arm, said means comprising a valve member and means accessible from the outside of said chamber for moving said valve member into and out of operative position.

14. A combined steam sleeve finishing board and puffer, comprising an elongated tubular arm, a source of steam, a hollow puffing iron, a support having a chamber, means for connecting the interior of the chamber with the source of steam, with the interior of the arm and with the interior of the puffing iron, a valve mechanism for closing the passageway from said chamber to the interior of the arm, said means comprising a valve member, means accessible from the outside of said chamber for moving said valve member into and out of operative position and means for heating the arm and puffer.

15. A steam sleeve board having a support (2), a member (3) secured to said support, the interior of said member being hollow so as to form a chamber (30), an elongated hollow arm (12) having its interior in communication with the interior of said chamber, a steam supply pipe (29) connected with the interior of the chamber at the side opposite from that to which the hollow arm is connected, a drain pipe (45) connected with the interior of the chamber at a point below the steam supply pipe and a partition (144) projecting into the chamber between the supply and the drain pipe.

16. A steam sleeve finishing board comprising, in combination, a support, an elongated arm secured to the support at one end and projecting outwardly therefrom, said arm having a continuous steam conduit extending along both sides thereof, a steam chamber intermediate said conduit, said chamber having a foraminated wall, means for conducting steam to one end of said conduit, means for providing a passageway between the other end of said conduit and said chamber and means comprising a valve for controlling the flow of steam through said passageway.

In testimony whereof I affix my signature.

IRWIN W. COX.
